Specification for Design.

Patented May 17, 1921.

Application filed October 12, 1920. Serial No. 416,562. Term of patent 7 years.

To all whom it may concern:

Be it known that we, GEORGE V. STRAHAN and FREDERICK W. MATHIEU, citizens of the United States of America, and residents, respectively, of the city of Newark, county of Essex, and State of New Jersey, and of the borough of Manhattan, city, county, and State of New York, have invented a new, original, and ornamental Design for a Canopy for a Lighting-Fixture, of which the following is a specification, reference being had to the accompanying drawing, forming part thereof.

The single figure of the drawing is a perspective view of a canopy for a lighting fixture, showing our new design.

We claim:

The ornamental design for a canopy for a lighting fixture, as shown.

GEORGE V. STRAHAN.
FREDERICK W. MATHIEU.
